R. C. UNDERWOOD

CABINET FOR TALKING MACHINE RECORD DISKS

Filed June 29, 1923

INVENTOR:

Roy Cornish Underwood

By Richards, Keen

Atty.

UNITED STATES PATENT OFFICE.

ROY CORNISH UNDERWOOD, OF SYDNEY, NEW SOUTH WALES, AUSTRALIA.

CABINET FOR TALKING-MACHINE-RECORD DISKS.

Application filed June 23, 1923. Serial No. 642,412.

To all whom it may concern:

Be it known that I, ROY CORNISH UNDERWOOD, subject of the King of Great Britain and Ireland, residing at T & G Building, 5 25^a Elizabeth Street, Sydney, New South Wales, Australia, have invented certain new and useful Improvements in Cabinets for Talking-Machine-Record Disks, of which the following is a specification.

10 This invention relates to record disk cabinets in which the disks are retained in vertical compartments by means of a pivoted bar and tend to roll forward when the bar is manually operated, and has been devised 15 to ensure rapid removal and replacement of any desired disk without undue effort or damage to the record surface or surfaces.

It has been found that inconvenience and damage to record disks while being inserted 20 into or removed from the compartments are due to warping or distortion of the partitions or walls of the compartments and to the consequent failure of the retaining stop or bar to act freely and quickly.

25 To overcome these defects I form the partitions of reinforced fibrous material and insert between each pair of partitions portion of a pivoted stop and release bar which is weighted at one end and I assist the action 30 of gravity on the bar by means of a resilient rod in contact with each bar.

By the use of reinforced partitions the 35 normal shape of the compartments is retained under even excessive variations in the temperature and humidity of the atmosphere thus permitting the disks to roll freely and the stop and release bars to act without extraneous friction.

The partitions may be formed of any desired fibrous material such as straw-or-mill-board, ply-wood, fibro-cement sheets or the like, and in each case the partition is reinforced with metal strips, metal or wood rods, wire meshing, corrugated or expanded 40 metal, or similar stiff material secured to or within the fibrous sheet in any convenient manner. The faces of each partition are covered with a soft lining to prevent injury to the record surfaces.

45 Each stop and release bar is approximately rectangular in longitudinal section but is weighted at one end and pivotally mounted so that one end normally projects within a compartment of the cabinet, the 50 outer end, which is manually operable, being provided with a groove on which an em-

bossed or raised numeral is formed corresponding to the number of the record held within the compartment. The stop and release bar is adapted to retain a record disk 60 wholly within a compartment when the bar assumes its normal tilted position, but, when moved out of this position, it permits the disk to roll forward until the disk again contacts with the bar. The disk is thereby 65 retained securely in this forward position with a segment of its surface projecting beyond the face of the cabinet; from this position it may readily be removed.

The stop and release bars may be mounted 70 across either the lower or the upper face of the cabinet. In the latter case the weighted end of each bar will project from the compartment and a rod to retain the disks in their projecting forward position 75 will be mounted across the lower face of the cabinet.

In the former case the retaining rod is not required as each bar serves to retain the disks in both their housed and their project- 80 ing positions.

In the accompanying drawing which illustrates one form of the invention:

Fig. 1 is a front elevation of a record cabinet forming portion of a cabinet talking machine;

Fig. 2 is a sectional side elevation showing a disk retained by a stop and release bar;

Fig. 3 is a similar view showing the operation of the stop and release bar;

Fig. 4 is a side elevation on a larger scale showing the mounting of a stop and release bar;

Fig. 5 is a front elevation corresponding to Fig. 4;

Fig. 6 is a side elevation of a portion of a partition showing one method of reinforcement.

Fig. 7 is a corresponding end elevation;

Fig. 8 is a side elevation similar to Fig. 6 with portion of one face of the partition broken away to show another form of reinforcement; and

Fig. 9 is an end elevation of portion of a partition reinforced as shown in Fig. 8.

The top and the bottom plates 10, 11 of the cabinet are mortised to receive partitions 12 which are suitably reinforced by metal strips 13 (Figs. 6 and 7) or wire mesh 13' (Figs. 8 and 9) and are covered with a soft lining not shown. Each partition may extend to the back of the cabinet or to a point

somewhat beyond the centre of each disk when the latter is fully housed.

The bottom plate is given a forward inclination of sufficient angle to ensure ready forward movement of a released record disk.

A spindle 14, mounted in lugs 15 on a projecting portion of end walls 16 or bottom plate 11 of the cabinet, carries a series of consecutively numbered stop and release bars 17 which are adapted to swing freely and independently about the spindle and may be loosely spaced thereon by means of distance pieces. I prefer, however, to form shoulders 18 on each side of the bars to prevent lateral displacement.

Each bar 17 is provided with a groove 19 on the upper surface of which a raised or embossed numeral 20 is formed without, however, extending to the top of the groove. Portion of the bar is reduced so that the outer arm of the bar is relatively weighted and tends to fall under the influence of gravity.

A rod 21, mounted near each of its ends on a spring 22 carried by the projecting portion of the side or bottom plate of the cabinet, is positioned between the spindle 14 and the cabinet and serves to elevate the inner ends of the bars 17.

The back wall of the cabinet is provided with a longitudinal buffer 23 of soft resilient material such as felt or the like to prevent damage to the disks 24 and to assist forward rolling when the disks are released.

While a disk is being inserted into a compartment the inner end of the bar 17 is depressed, but when the disk reaches its inmost position the resiliently mounted rod 21 and the downward pull of gravity on the outer end of the bar 17 will immediately force the inner end of the bar upwards to function as a stop and prevent return movement of the disk as shown in Fig. 2.

To release a required disk from the cabinet the outer end of the correspondingly numbered bar 17 is raised whereupon the disk, assisted by the slight outward pressure of the buffer 23, rolls forward and is retained by the bar 17 with the front portion of the disk projecting beyond the cabinet. (Fig. 3).

The disk record cabinet may be formed as an independent structure or as portion of existing cabinet talking machines. In the

former case side and back walls are necessary and are secured to each other in any suitable manner, but in the latter case only top and bottom plates are essential, the sides and back of the main cabinet serving as side and back walls for the inner disk record cabinet, or reinforced partitions may be used as side walls. The forwardly sloping bottom plate may be inserted above a fixed horizontal bottom plate and retained in position by any suitable means.

What I claim as my invention and desire to secure by Letters Patent is:—

1. A cabinet for receiving talking machine record disks including a plurality of partitions forming disk receiving compartments, an inclined bottom for said compartments, a pivot arranged in front of said compartments, a plurality of stop bars mounted on said pivot and each individual to one of said compartments, each bar being weighted at its forward end which projects outwardly beyond said partitions and which is capable of being grasped to actuate the bar, and the inner end of said bar normally projecting into its compartment in an upwardly inclined position and capable of engaging a disk to retain the same wholly within its compartment, and a spring pressed bar supported upon the bottom of the cabinet and engageable with said stop bars to exert a constant upward pressure upon the inner ends thereof.

2. A cabinet for talking machine record disks comprising a top plate, a forwardly sloping bottom plate, reinforced vertical partitions mounted on said top and bottom plates, an unbalanced pivoted stop bar tilted by gravity with its lighter end projecting between each pair of partitions and its heavier end in front of and below the level of the lower ends of the partitions, a rod extending across the front of the cabinet beneath the pivoted stop bars, and a resilient member mounted below each end of the rod and exerting an upward pressure thereon to maintain said rod in yielding engagement with said stop bars.

In testimony whereof I affix my signature in presence of two witnesses.

ROY CORNISH UNDERWOOD.
